METHOD OF MAKING A CONTAINER

Arnold Robert Rein and Roland Norbert Wendricks, Barrington, Ill., assignors to American Can Company, New York, N.Y., a corporation of New Jersey

Filed Dec. 26, 1962, Ser. No. 246,919

8 Claims. (Cl. 93—55.1)

This invention relates to the manufacture of containers of fibre or similar pliable materials used for the packaging of liquids, such as milk and juices, and has particular reference to a method of constructing such a container having a tubular body and a substantially flush, telescopically fitted end closure.

A principal object of this invention is the provision of a method of making a sanitary container wherein the top end closure is substantially planar in configuration and is secured to the tubular body in a flush, leak-proof joint which provides for shedding liquid or other foreign matter to prevent unsanitary fouling and unsightly appearance.

Another object of this invention is the provision of an improved method of assembly of a fibre container body and end closure adaptable to assembly at the dairy or packer's own facility.

Another object of this invention is the provision of an improved method of assembling fibre containers to produce a leak-proof joint in a simple and efficient manner without extensive forming and sealing equipment.

Still another object of this invention is the provision of a method of assembling fibre containers, which method is readily performed in the packer's own facility and is suitable for incorporation into packaging lines with a minimum of modification to existing equipment.

Numerous other objects and advantages of the invention will be apparent as it is better understood from the following description, which, taken in connection with the accompanying drawings discloses a preferred embodiment thereof.

With these objects in view, the present invention contemplates a method of making containers by forming a tubular body having marginal flanges extending from its side walls, partially deforming these extending flanges inwardly along lateral fold lines at the end of the body, bringing into position over the inwardly deformed flanges an end closure having a planar panel and side flaps adapted to be folded at right angles against the body walls, moving the body and the closure relatively together to fully deform the flanges into underlying securement with the panel, and folding and securing the flaps against the body walls to provide a flush, leak-proof end joint.

Referring to the drawings:

FIG. 1 is a perspective view of a container made in accordance with the present invention.

FIG. 2 is a fragmentary plan view of the body blank used in the container of FIG. 1.

FIG. 3 is a plan view of the top end closure blank used in the container of FIG. 1.

FIG. 4 is a fragmentary sectional view taken substantially along line 4—4 of FIG. 1.

FIG. 5 is a view showing the components of the container of FIG. 1 in position just prior to their assembly, and illustrates one arrangement of means for practicing the present invention.

FIG. 6 is an enlarged plan view of one corner of the container taken substantially along line 6—6 of FIG. 5.

FIG. 7 is an enlarged, fragmentary sectional view showing the container components being moved together in the initial stage of their assembly.

FIG. 8 is a view similar to FIG. 7, showing the components fully assembled.

The container and its components illustrated in FIGS. 1—4 are of the generally preferred construction to which

2

the present invention relates. A container of this general configuration is disclosed in U.S. Patent No. 2,346,684 issued April 18, 1944 to J. M. Hothersall on Container. As shown, it comprises a tubular, rectangular body generally designated 10, a substantially planar top end closure generally designated 11 telescopically fitted to the end of the body, and a hinged closure 12 secured to the top end 11 in registry with a pouring opening 13 formed therein. A bottom end closure 15 completes the container structure.

Body 10 is fabricated from a pre-formed body blank 10' as illustrated in FIG. 2. This blank comprises side panels 16 defined by parallel fold lines 17 and integral flanges 18 extending from the side panels. A relatively wide fold or score line 19 extends the length of the blank at the juncture of flanges 18 and panels 16. Flanges 18 are formed by notching the blank at the terminus of each longitudinal score line 17, thereby providing the adjacent flanges with angular edges 20 which converge to an apex at the terminus of score line 17. It has been found that the notch angle should slightly exceed 90° and the apex of the notch should extend to the inner side of score line 19, this construction avoiding crowding or wrinkling of the fibre material when the flanges are folded and providing a smooth abutment of edges 20 in the finally formed seam. A glue or adhesive strip 21 may be applied along the length of the blank parallel to and contiguous score line 19.

Top end closure 11 is provided in the form of a planar blank 11' illustrated in FIG. 3. This blank comprises a central flat panel 22 dimensioned to correspond to the cross section of tubular body 10 and marginal flaps 23 extending from its sides. Score or fold lines 24 are formed at the juncture of the flaps with panel 22, and the blank is notched at each corner to form the end edges 25 of the flaps. A suitable adhesive or glue 26 is coated to the underside of the blank so as to cover the peripheral margin of panel 22 and preferably extends outwardly over each of the flaps 23. If desired, sufficient adhesive may be applied to the flaps so that the adhesive strip 21 on body 10 is not necessary. Alternately, flaps 23 may be left entirely free of adhesive, in which case adhesive 26 is applied only to panel 22 and the adhesive 21 on body 10 is relied on for securing the flaps to the body walls.

In the assembly of the container illustrated in FIG. 1, body blank 10 is first shaped into tubular configuration in any suitable manner, an example being by folding it at right angles along fold lines 17 on a mandrel or like fixture and sealing its opposed transverse edges in a lapped side seam 27. The blank may be dimensioned and formed so that side seam 27 is disposed either in one of the side walls of body 10 or at one of its corners. Top end closure 11 is then assembled to body 10, in a manner next to be described, to form a substantially flush, right angle end joint as illustrated in FIG. 4. In this construction, body flanges 18 are fully deformed inwardly at right angles to body walls 16 to underlie and engage closure panel 22. Similarly, closure flaps 23 are bent downwardly at right angles to telescopically conform to body side walls 16. The notch edges 20 and 25 of the body flanges and closure flaps, respectively, are brought into abutting contact when the components are assembled. Adhesive strip 26 (and also 21 if used) not only secures the components together but also is made to flow over the edges of body flanges 18 as at 28 to protect these edges against moisture attack and to partially flow as at 29 and 30 between the edges 25 of the closure flaps 23 and between the edges 20 of body flanges 18 to fill these interstices and fully caulk the seam joint.

The preferred method of effecting this type of assembly is illustrated in FIGS. 5—8, wherein is shown an arrangement for moving body 10 and closure blank 11' rela-

tively together and forming the top end seam. This comprises a reciprocable platform 40 on which body 10 is supported in upright position by registering bars 41, a telescoping die generally designated 42 disposed above the platform in axial alignment with body 10, heating means 43 positioned between the die and platform and adapted to extend about the container body, and cross feed means 44 for successively feeding end closure blanks 11' from a magazine M into position between the die 42 and the top end of body 10.

Die 42 is provided with a cavity 45 which opens toward platform 40 and which is the same general cross-sectional configuration as that of tubular body 10 but slightly larger in dimension to accommodate the thickness of closure flaps 23. The die cavity is provided with tapered walls 46 which extend from the open end of the cavity inwardly a predetermined distance to merge with straight walls 47. The face of die 42 nearest platform 40 is recessed as at 48 to receive a resilient or rubber-like member 49 which surrounds cavity 45. A conduit line 50 may communicate with cavity 45 to provide a slight vacuum therein to facilitate registering and holding closure blanks 11' in proper alignment as they are successively shifted into position onto resilient member 49. Conduit 50 also may provide the means for venting the die cavity to facilitate entry of the components therein as they are assembled.

Heating means 43 is here shown in the form of a manifold surrounding container body 10 and is provided with a plurality of orifices 51 for emitting heated air or the like against the respective, cooperating surfaces of body 10 and closure blank 11'. Orifices 51 are appropriately positioned to heat and thereby activate adhesive strip 26 on the bottom surface of blank 11' and to heat the upper surface of body flanges 18. If body 10 is provided with adhesive strip 21 as hereinbefore described, the orifices may be adjusted in size or position to also activate this adhesive.

Prior to moving body 10 and closure blank 11' together, body flanges 18 are given an initial and partial inward deformation to rigidify the body. These flanges are turned inwardly along fold line 19 at an angle less than the right angle which they will ultimately assume but are deformed a sufficient amount so as to remain in an unrestrained, inward inclination. This is an important feature in that it permits the assembly of the end closure without the use of an internal support or without the necessity of deforming the body walls in the end seam area in order to obtain adequate sealing pressure. It has been found that when body flanges 18 are initially deformed, body 10 possesses sufficient rigidity of itself to permit the fitting and securing of closure 11 in a flush, leak-proof seam.

With closure blank 11' positioned across the open end of die cavity 45 in registry with body 10, manifold 43 is operated for a period sufficient to render adhesive 26 pliable. Platform 40 then moves toward the die to bring the body into contact with the closure blank, as shown in FIG. 7. Body flanges 18 are the first to make contact and, because of their inclined attitude, are caused to plow into and slide through adhesive 26 as they press against the lower surface of closure blank 11'. The raw edge of each flange thereby moves inwardly to build up a deposit of adhesive at 28, which deposit adheres to these edges when flanges 18 reach their full right angle deformation to provide protection against exposure of these edges to the contents of the container.

At this point in the assembly operation, the pressure exerted against closure blank 11' is minor so that flaps 23 react against resilient element 49 with only slight downward deformation. Continued upward movement of body 10, however, forces closure blank 11' upwardly into die cavity 45 so that flaps 23 are pulled first through member 49, then upwardly against tapered walls 46, and finally into the innermost end of the cavity against straight

walls 47 (see FIG. 8). This upward wiping movement forces closure flaps 23 downwardly into telescoped engagement with the margins of body side walls 16 where, after a brief instant to allow the adhesive to set, they become permanently secured. During this movement, the inclination of body flanges 18, which increases to a full right angle as the components move together, stiffens body 10 sufficiently to provide reactive pressure against closure flaps 23. When they reach their full right angle position, body flanges 18 press tightly against closure panel 22 and become secured there as the adhesive sets. Thus, a simple assembly is accomplished without the need for high sealing pressures or for drastically deforming any of the container components, and provides a flush, fully caulked end seam of excellent abuse resistance and leak-proof quality.

Although the above description has been directed primarily to the top end closure and its assembly to the container body, it will be understood that bottom end closure 15 may be of similar configuration and secured to body 10 in the same manner. As a practical matter, however, the bottom end is usually the first to be assembled and permits greater flexibility in its construction and method of securement to the container body. That is, the interior of the body is readily accessible for assembly of the first end closure so that a mandrel or other internal support fixture may be used to provide forming and sealing pressure without difficulty. Accordingly, bottom closure 15 may be provided in the form of integral flaps extending from the bottom of the side panels of a preformed body blank or, for that matter, may be the type of construction disclosed in the hereinbefore referred to Hothersall patent. Whichever the case, an insertible fixture may be used, if preferred, for internal support and sealing pressure, whether the container is to be assembled in the packer's facility or otherwise fabricated. Top end closure 11, on the other hand, cannot be assembled with the aid of an internal fixture, at least one of practical design, and is therefore ideally suited for assembly by the method of this invention.

It is thought that the invention and many of its attendant advantages will be understood from the foregoing description and it will be apparent that various changes may be made in the steps of the process described and their order of accomplishment without departing from the spirit and scope of the invention or sacrificing all of its material advantages, the process hereinbefore described being merely a preferred embodiment thereof.

We claim:

1. A method of making containers, which comprises the steps of providing a tubular body having marginal flanges extending from its side walls, partially deforming said flanges inwardly along lateral fold lines where said flanges and walls are joined to initially rigidify said body, positioning over said flanges an end closure having a planar panel and side flaps extending therefrom in registry with said side walls, moving said body and said closure relatively together to fully deform said flanges into parallel planar relationship and underlying securement with said panel, and folding and securing said flaps against said side walls.

2. The method of claim 1 wherein said flanges and said flaps are deformed into their respective positions and secured by bringing said body and closure together in one continuous, relative movement.

3. The method of claim 1 wherein said flanges are initially inwardly deformed to an unrestrained position and thereafter fully deformed at right angles to said walls by the pressure of contact with said panel as said closure and body move relatively together.

4. The method of claim 2 wherein said body and said closure are assembled solely by externally applied, opposed forces acting on said body in the direction of said closure and against said flaps in the direction of said body.

5. A method of making containers, which comprises

the steps of providing a tubular body having marginal flanges extending from its side walls, partially deforming said flanges inwardly of said walls to an unrestrained position, positioning over said flanges an end closure having a planar panel with side flaps extending therefrom in registry with said side walls and a coating of pliable adhesive on its surface nearest said flanges, and assembling said body and said closure by moving the two relatively together to first bring the edges of said partially deformed flanges into sliding contact with said adhesive and then to fully deform said flanges and said flaps into secured engagement with said panel and said side walls, respectively.

6. A method of making fibre containers, which comprises providing a tubular body having marginal flange portions extending from its side wall and externally supporting said body with said flange portions projecting toward a telescoping die, positioning between said body and the die and end closure having a planar panel with peripheral portions adapted to be folded over the side of said body and a heat-softened adhesive on the margins of its surface nearest said flange portions, heating said adhesive to render it pliable, moving said body and said closure relatively together to bring the edge of said flange portions into contact with said pliable adhesive, and moving said closure and said body together into said die to fold and secure said peripheral portions over the wall of said body and to deform said flange portions inwardly into underlying securement with said panel, said edge of said flange portions thereby being caused to slide inwardly through said adhesive to caulk said edges and any interstices present in the resulting seam.

7. A method of fabricating tubular containers of pliable material such as fibre, comprising the steps of forming a body blank having side wall portions with an integral, trapezoidal flange extending from an end of each side wall portion, forming said blank into tubular configuration along longitudinal fold lines and securing its opposed longitudinal edges together to provide a tubular body, folding said flanges inwardly along fold lines formed transversely of said wall portions at said end to rigidify

5 said body, positioning over said flanges an adhesive bearing closure blank having a central panel substantially equal to the exterior cross dimensions of said body with an integral, rectangular flap extending from each of its sides, activating said adhesive to render it pliable, moving said body and said closure blank relatively together to bring said flanges into contact with the peripheral margin of said panel, continuing to move said body against said panel solely by externally applied pressure while restraining said flaps to fold said flaps telescopically over said side wall portions to form an end closure and cause said pliable adhesive to migrate between the cooperating surfaces of said body and said closure, and temporarily holding said body and said closure under externally applied pressure to allow said adhesive to set to provide a substantially flush, fully caulked, leak-proof seam.

10 8. In the method of assembling a fibre container having a leak-proof joint between a tubular container body having discrete flanges appended to each of the body walls and an adhesively coated container end closure having discrete flaps appended to the end closure central panel and being transversely coincident with said container body walls, the steps comprising aligning said end closure in spaced relationship over said container body, folding said flanges inwardly an acute angle from the plane of said body walls, activating said end closure adhesive to render it pliable, moving said body and said end closure relative to one another to cause the edges of said inwardly folded flanges to slide through said activated adhesive and thereafter to cause said flanges to fold further inward to form substantially right angles with said body walls and to thus be parallel to and adhesively secured to said end closure central panel, and continuing said relative movement to cause said flaps to fold downward to form substantially right angles with said end closure central panel and to thus be parallel to and adhesively secured to said body walls.
